DESIGN FOR A SHOE

John Richard Morgan, Oak Park, Ill., assignor to
Sears, Roebuck and Company, Chicago, Ill., a
corporation

Application November 21, 1935, Serial No. 59,686

Term of patent 3½ years

To all whom it may concern:

Be it known that I, John Richard Morgan, a citizen of the Republic of Guatemala, residing in the village of Oak Park, in the county of Cook and State of Illinois, have invented a new, original, and ornamental Design for a Shoe, of which the following is the specification, reference being had to the accompanying drawing, forming part thereof.

Figure 1 is a perspective view of a shoe showing my new design; the opposite side of which is sub-

stantially the same in appearance as the side shown;

Figure 2 is a bottom plan view of the shoe, it being understood that the ornamental features shown on one-half of the shoe sole are to be extended over the portion shown in broken lines.

I claim:

The ornamental design for a shoe substantially as shown and described.

JOHN RICHARD MORGAN.
